DESIGN FOR A PROJECTOR OR SIMILAR ARTICLE

George Kende, New York, and Everett M. Porter,
Brooklyn, N. Y., assignors to Universal Camera
Corporation, New York, N. Y., a corporation of
New York

Application August 7, 1936, Serial No. 64,286

Term of patent 14 years

To all whom it may concern:

Be it known that George Kende and Everett M. Porter, citizens of the United States and residents respectively of New York city, in the county of New York and State of New York, and Brooklyn, in the county of Kings and State of New York, have invented a new, original, and ornamental Design for a Projector or Similar Article, of which the following is a specification, reference being made to the accompanying drawing forming part thereof, in which,

Fig. 1 is a perspective view of a projector embodying our new design, illustrating the front and one side thereof,

Fig. 2 is a side elevational view of the opposite side of the projector shown in Fig. 1 but showing in dotted lines only the outline of the two reels shown completely in dotted lines in Fig. 1.

Fig. 3 is a view showing the rear of the projector illustrated in Fig. 1.

We claim:

The ornamental design for a projector or similar article substantially as shown and described.

GEORGE KENDE.
EVERETT M. PORTER.
